UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING APPARATUS.

1,378,362.

Specification of Letters Patent. Patented May 17, 1921.

Application filed June 11, 1917, Serial No. 174,088. Renewed September 11, 1920. Serial No. 409,700.

To all whom it may concern:

Be it known that I, NILS D. LEVIN, a citizen of the United States, residing at Columbus, in the county of Franklin and State of Ohio, have invented certain new and useful Improvements in Mining Apparatus, of which the following is a specification, reference being had therein to the accompanying drawing.

10 The present invention relates to certain new and useful improvements in mining apparatus of the class in which each comprises a cutting mechanism adapted to lateral bodily movement relative to the coal face while cutting, and a wheeled truck adapted to carry the said cutting mechanism from place to place and to guide and control its cutting movement relative to the coal while remaining upon the track.

15 I am aware that machines have been proposed wherein the weight of the entire apparatus, including the cutting mechanism, is carried by the truck not only during transportation but also during the cutting operation. With its weight carried by the truck it is impossible to permit the cutting mechanism to project beyond the outlines of the base through more than a certain relatively small distance, and consequently the 20 width of the room or entry which can be cut by such a machine is quite limited.

In my co-pending application, Serial No. 9972, filed February 23, 1915, is disclosed an apparatus in which the cutting mechanism 25 can be carried upon the truck during transportation and in which it is removable horizontally therefrom without breaking its connection therewith to rest entirely upon the floor and be moved horizontally under the 30 guidance and control of the truck to cut a horizontal kerf from one side to the other of a relatively wide room.

In coal mines break throughs, or connecting passages, are formed at regular intervals in the walls between adjacent rooms and between parallel adjacent entries, through which is maintained the circulation of air necessary to the ventilation of the mine. The formation of these break 40 throughs necessitates the occasional operation of the cutting mechanism along the side walls of the rooms and entries in lines parallel to their length. By the earlier machines falling within the above definition 45 the cutting of such break throughs could

only be accomplished by entirely disconnecting the cutting mechanism from the truck and laboriously moving it by means of bars, cables, etc., into the desired cutting position, and after the completion of the cutting operation, moving it back in like manner to a position from which it might be reloaded upon the truck.

It is the especial object of this invention to provide an apparatus in which the cutting mechanism can be carried by the truck during transportation and in which it is movable horizontally therefrom without breaking its connection therewith to rest entirely upon the floor and to be moved 65 horizontally under the guidance and control of the truck to cut a horizontal kerf from one side to the other of a relatively wide room or to cut a horizontal kerf longitudinally of the side wall of a relatively narrow 70 room.

The devices by which I attain this object are fully set forth in the following specification and illustrated in the accompanying drawings of which

80 Figure 1 is a side elevation of the preferred embodiment of my invention showing the cutting mechanism loaded upon the truck for movement from one place to another.

85 Fig. 2 is a fragmentary side elevation of the devices shown in Fig. 1 showing the cutting mechanism in position for cutting across the face of a mine room.

Fig. 3 is a plan view of the devices shown 90 in Fig. 2.

Fig. 4 is a side elevation of the cutting mechanism in position to begin its sumping, or entering, cut.

Fig. 5 is a plan view of the main base 95 part of the truck with some of the mechanism carried directly thereby, the swinging, supporting and guiding devices for the cutting mechanism being removed.

Fig. 6 is a plan view of the turn table and 100 tilting frame of the truck.

Fig. 7 is a plan view of the swinging, supporting and guiding devices for the cutting mechanism.

Fig. 8 is a fragmentary view showing a 105 detail of the supporting and guiding devices for the cutting mechanism.

Fig. 9 is a cross section along the line 9—9 of Fig. 3.

Fig. 10 is a fragmentary elevation show- 110

ing the connections between the mining machine and the truck propelling mechanism.

Figs. 11 to 21 inclusive are diagrams illustrating the method of operating the apparatus.

Like numerals refer to similar parts in the several figures.

In the drawings the numeral 1 indicates, as an entirety, a mining machine adapted 10 to form a horizontal kerf across the coal face, the numeral 2 indicates a truck adapted to travel along the rails 3 of the mine track to support said mining machine for transportation and, while still supported 15 upon the said track rails, to serve as an abutment for the guiding and controlling devices indicated by the numerals 4, 5 and 6. The mining machine 1 comprises a main frame 7 from which projects the cutting 20 mechanism 8 adapted to be thrust longitudinally into the coal body and to be then moved laterally to form a kerf therein. Upon the main frame 7 is mounted a suitable motor 9 which may be of any preferred 25 type for the actuation of the machine. The main frame 7 of the mining machine rests upon and is slidable longitudinally of the bottom pan 6 which is provided with up-standing flanges 10 to engage the sides of 30 the mining machine frame and prevent its lateral movement relative to the said bottom pan. Longitudinal skid bars 11 are attached to the bottom pan to afford a sliding support along which the mining machine 35 may be easily moved. A latch bolt 12 hinged to the main frame 7 of the mining machine is adapted to engage with the notches 13 in the flange 10 when the mining machine is in its extreme position at either 40 end of the bottom pan 6. By the engagement of this latch bolt 12 the machine is held against longitudinal movement in the pan during the lateral cutting operation and during transportation. The bottom pan 45 6 is pivotally mounted upon the sliding frame 5 which is adapted to rest upon and slide over the floor of the mine during the cutting operations of the machine, and to slide along the tilting frame 4 when the 50 machine is being loaded upon the truck. The sliding frame 5 consists of a heavy steel plate the edges of which are turned upward to form flanges 14 which both stiffen the plate and facilitate its sliding upon the 55 floor of the mine. A pivot casting 15 riveted to the plate 5 engages an aperture of the bottom pan to form its pivotal attachment, and a cap piece 16 attached to the pivot casting 15 engages the upper surface of the 60 bottom pan to prevent its accidental displacement. Attached to the rearward edge of the sliding frame 5 are steel castings 17 upon which are formed hooks 18 adapted to engage the upstanding flanges 19 of the 65 longitudinal angle bars 20 of the tilting

frame 4. At the forward end of the longitudinal angle bars 20 are shoe castings 21 adapted to engage and slide upon the floor of the mine when the tilting frame 4 is in its tilted position. Formed on the shoe 70 castings 21 are wings 22 adapted to engage the hooks 18 of the sliding frame to limit their forward movement along the angle bars 20. Removable pins 23, placed in suitable apertures of the wings 22, lock the 75 hooks 18 against rearward movement during the cutting operations of the machine. The longitudinal angle bars 20 are joined together near their ends by cross members 24 and 25 to form a rigid rectangular frame, 80 and to the side flanges 19 are attached trunnions 26 by which said frame is supported in the hinge castings 27 fixed to the forward end of a heavy steel plate 28 of the truck 2. The truck 2 consists of a rectangular 85 frame formed of the side sills 29 and cross members 30, 31 and 32. To the side sills are secured the journal bearings 33 in which are journaled the supporting axles 34. To the axles 34 are fixed traction wheels 35 which 90 support the truck upon the rails 3 of the mine track. Carried by the cross members 30 and 31 is a pivot post 36 which extends through a suitable aperture in the plate 28 to pivotally attach it to the truck, thereby 95 forming a turn table upon which the mining machine and guiding mechanism may be rotatably supported. The pivot post 36 is provided with a head 36^a which engages the upper surface of the turn table plate 28 to 100 prevent its accidental displacement and also provides a non-rotative step bearing for the lower end of a suitable anchor jack 36^b by which the truck may be secured in any preferred position.

Supported upon the cross member 32 at the rearward part of the truck is a gear housing 37 within which is mounted a suitable transmission gearing arranged to connect the motor of the mining machine with 110 the truck axle 34 to propel the truck along the tracks of the mine. Journaled in this gear housing is a longitudinal shaft 38 connected with the said transmission gearing and having at its forward end a clutch member 39 arranged to connect with a complementary clutch member 40 upon the projecting end of the armature shaft of the motor 9 when the mining machine is in position for transportation upon the truck 2. The 115 clutch member 40 has a conical projection 41 adapted to engage with a complementary recess of the clutch member 39 to insure the correct alignment of the rotating parts. Upon the clutch members 39 and 40 are 120 formed annular flanges 42 and 43 perforated with a plurality of spaced registering apertures through which may be thrust the clutch pins 44 to rotatively connect the members 39 and 40. The clutch pins 44 are carried by 125 130

a shifting ring 45 adapted to slide longitudinally upon the hub 46 to facilitate their insertion and withdrawal from the apertures of the flanges 42 and 43. Hinged to 5 the housing casting 37 is a hook 47 adapted to engage a lock member 48 formed upon the motor casing, to prevent longitudinal movement of the motor relative to the gear housing and the consequent disengagement 10 of the clutch members. Upon the hook member 47 is formed a lug 49 adapted, when in locked position, to engage the shifting ring 45 to prevent the accidental withdrawal of the clutch pins 44. Mounted in the gear 15 housing 37, and connected with the aforesaid transmission gearing, is a transverse shaft 50 upon the projecting end of which is fixed a sprocket wheel 51 connected by a suitable endless driving chain 52 with the sprocket 20 wheel 53 upon the axle 34 to propel the truck 2. Idler sprockets 54 and 55, mounted upon the longitudinal member 29 of the truck frame, deflect the driving chain 52 to allow the tilting frame 4 to be freely swung in 25 either direction upon the turn table 28 before tilting.

My invention is not limited to a kerf cutter of any particular type, but there are many advantages incident to the use of a 30 completely separable and independently operable mining machine which can be connected to the guiding and controlling devices of the invention or which can be disconnected therefrom and used independently. 35 In the drawings I have shown a mining machine of well known construction of the short wall type but as the details of its construction form no part in the present invention extended description is not thought to be 40 required at this time, and it will be sufficient here to refer briefly to the more important parts. 7 is the main frame upon which is suitably mounted an electric motor 9 adapted to receive its actuating current through 45 a flexible conductor cable 56 from any convenient source of electric supply. Electric controlling apparatus 57 is mounted upon the side of the mining machine to control the motor 9 and is provided with an operating 50 handle 58 convenient to the hand of the operator. A winding drum 59 is mounted upon the inner end of the mining machine frame and is connected through gearing not shown in the drawing with the motor 9. 55 Windable upon the winding drum 59 is a rope 60 the free end of which is adapted to be connected to any suitable anchor toward which it is desired to move the machine. Guide sheaves 61, 62 and 63 are provided 60 upon the mining machine frame to lead the feed rope 60 in any desired direction. A second winding drum 64 is provided upon the rearward part of the mining machine frame and upon this is windable a guide 65 rope 65 the unwinding of which may be retarded by frictional elements 66 to resist the movement of the outer end of the mining machine frame when it is operated independently of my improved guiding devices. The cutting mechanism 8 is of the 70 well known chain cutter type having an elongated supporting frame along the edges of which travels an endless chain 67 to which is attached renewable cutting bits 68 by which the coal is cut. The cutter chain 67 75 passes around a sprocket wheel, not shown in the drawing, which is connected through suitable gearing with the motor 9.

In Figs. 11 to 17 inclusive I have shown the preferred method of operating this apparatus in the relatively wide rooms of a coal mine. The truck with the mining machine loaded upon it, as illustrated in Fig. 1 of the drawings, on arriving at the working place, is positioned near the working 80 face as illustrated in Fig. 11. The machine is then rotated upon the turn table 28 to the position illustrated in Fig. 12, so that the cutter arm 8 will extend toward the point at which the cutting is to begin. The feed 85 rope 60 is then drawn out from the winding drum 59 passed around the guide sheaves 61 and 62 and attached to the hooks 69 at the forward end of the shoe casting 21. Upon the actuation of the winding drum the draft 90 upon the rope 60 will cause the sliding frame 5, and with it the bottom pan 6 and the mining machine, to move forward relative to the truck. As these parts move forward and the center of gravity passes the hinge 95 member 27 the tilting frame 4 will tilt to the position illustrated in Fig. 20. The forward end of the bottom pan will continue to slide forward upon the floor of the mine until the parts assume the relation shown in 100 Figs. 4 and 13 of the drawings. The feed 105 cable 60 is then disconnected from the hook 69, again drawn out from the winding drum, and connected to the hook 70 at the forward end of the bottom pan as shown in Fig. 4. 110 The pin 23 is then inserted in the aperture of the shoe casting 21 to prevent rearward movement of the sliding frame 5 relative to the tilting frame 4, the latch bolt 12 is lifted out of engagement with the notch 13 of the 115 flange 10, the cutting mechanism is started and the winding drum again actuated to wind the rope 60 to draw the machine longitudinally forward to form the sumping or entering cut. After the sumping cut has 120 been completed and the latch bolt 12 engaged in the forward notch 13, the feed rope 60 will be again drawn out from the winding drum 59 and connected to a suitable abutment, such as the jack post 71, at the left 125 hand side of the room, as shown in Fig. 15. The draft upon the feed rope will then cause the machine to move laterally across the face of the room, rotating about the turn table 28, the truck serving as an abutment 130

to hold the machine in proper relation to its work as illustrated in Fig. 16. It is obvious that jacks similar to the jack 36^b may be placed against any preferred part of the 5 truck to hold it in position as is the common practice with mining machines generally, their number and arrangement depending on local conditions and the opinion of the operator, and it is not thought to be necessary to show such jacks in the drawings. 10 When the cut has been completed across the room, the feed cable may be passed around the guide sheaves 61 and 63 and connected to the abutment 72 at the rear end of the 15 tilting frame as is shown in Fig. 17 and the machine may be reloaded upon the truck by its own power.

Under some circumstances, as for example when cutting at the end of an entry, it is 20 desirable that the side walls shall be maintained in straight lines parallel to the general direction of the entry. In such a case the machine may be positioned as shown in Fig. 21 and the sumping cut made in the 25 same manner as above described. After the sumping cut has been completed the feed rope 60 will be drawn out from the winding drum 59 and attached to an anchor jack 71 suitably placed in the direction toward 30 which it is desired to feed the machine. The retarding rope 65 is then drawn out from the drum 64 and attached to a suitable anchor jack 74 at the rear of the machine. The operation of the machine will then proceed 35 as in ordinary short wall work, tension on the feed rope 60 moving the machine laterally to cut the coal and tension upon the retarding rope 65 maintaining the angular relation of the cutter arm 8 with the coal face. 40 The tilting frame 4 will rotate about the turn table 28 causing the mining machine to move in an arcuate path as indicated in Fig. 21. After the completion of the cut 45 the mining machine can be reloaded upon the truck in the same manner as above described.

In Fig. 18 I have shown a method of operation for the purpose of cutting a break through in the left hand rib of an entry. 50 The unloading of the machine for such an operation is performed in the same manner as when cutting in a room, and is shown in Figs. 11, 12, 13 and 14. After the sliding frame 5 and bottom pan 6 have reached their 55 extreme outward position the bottom pan may be rotated about the pivot center 16 until the cutter arm 8 points toward the place at which the cutting is to begin. The sumping cut is then made in the same manner as when cutting in a room. After the 60 completion of the sumping cut the feed rope 60 is drawn out from the winding drum 59 and attached to a suitable anchor jack 73 placed adjacent the rib in the direction toward 65 which the cutting is to proceed. The

retarding rope 65 is then drawn out from the drum 64 and attached to a jack 74 suitably placed in the rear of the machine. The cutting operation then proceeds as in ordinary short wall operation, the strain on the 70 feed rope 60 moving the machine to cut the coal and the resistance of the retarding rope 65 maintaining the angular relation of the cutter arm 8 to the coal rib.

After the coal which was under cut by the 75 operation illustrated in Fig. 18 has been removed a second cut may be made in the manner illustrated in Fig. 19, the tilting frame in this case being swung to the left instead of to the right before unloading the 80 mining machine.

It is obvious that this apparatus is capable of many other operations but it is thought that the above examples sufficiently illustrate the invention here set forth.

85

What I claim is:

1. In a mining apparatus, the combination of a transporting truck adapted to travel over mine tracks, a complete separately operable mining machine having a 90 relatively fixed horizontally projecting kerf cutting mechanism and adapted to rest in a predetermined position on the truck or to move off the truck and advance bodily relative to the coal face to cut a kerf therein, 95 intermediate guiding devices comprising laterally rigid elements pivotally connected to the truck and adapted to guide the mining machine off of and onto the truck and to guide it transversely relative to the 100 truck during its cutting operations, and pivotal devices associated with said guiding devices to permit movement of the cutting mechanism transversely of said laterally 105 rigid element.

2. In a mining apparatus, the combination of a transporting truck adapted to travel over mine tracks, a complete separately operable mining machine having a 110 relatively fixed horizontally projecting kerf cutting mechanism and adapted to rest in a predetermined position on the truck or to move off the truck and advance bodily relative to the coal face to cut a kerf therein, 115 intermediate guiding devices comprising laterally rigid elements pivotally connected to the truck and adapted to guide the mining machine off of and onto the truck and to guide it transversely relative to the truck during its cutting operations, pivotal devices 120 associated with said guiding devices to permit movement of the cutting mechanism transversely of said laterally rigid elements, and means to maintain the kerf cutting mechanism in any desired angular relation 125 with the coal face.

3. In a mining apparatus, the combination of an abutment frame adapted to be anchored in fixed position, a complete separately operable mining machine having its 130

- weight supported independently of the abutment frame and having a relatively fixed horizontally projecting kerf cutting mechanism, guiding devices comprising laterally rigid elements pivotally connected with the abutment and engaging said mining machine to guide it rotatively about the abutment, and pivotal devices associated with said laterally rigid elements to permit movement of the kerf cutting mechanism transversely of the guiding devices. 10
4. In a mining apparatus, the combination of an abutment frame adapted to be anchored in a fixed position, a complete separately operable mining machine having its weight supported independently of the abutment frame and having a relatively fixed horizontally projecting kerf cutting mechanism, guiding devices comprising laterally rigid elements pivotally connected with the abutment and engaging the mining machine to guide it rotatively about the abutment, pivotal devices associated with said guiding devices to permit movement of the kerf cutting mechanism transversely of said laterally rigid elements, and means to maintain the kerf cutting mechanism in any desired angular relation with the coal face. 20
5. In a mining apparatus, the combination of a transporting truck adapted to travel over a mine track, a complete separately operable mining machine having a relatively fixed horizontally projecting kerf cutting mechanism and adapted to rest in a predetermined position on the truck or to move off the truck and advance bodily relative to the coal face to cut a kerf therein, intermediate guiding devices comprising laterally rigid elements pivotally connected to the truck and adapted to guide the mining machine transversely relative to the truck during its cutting operation, and pivotal devices associated with said guiding devices to permit movement of said cutting mechanism transversely of said laterally rigid elements. 30
6. In a mining apparatus, the combination of a truck adapted to travel over a mine track, a horizontally projecting kerf cutter adapted to have its weight supported upon the truck or independently thereof, intermediate guiding devices comprising laterally rigid elements pivotally connected to the truck and adapted to guide the kerf cutter transversely of the coal face during its cutting operation while supported upon the truck or independently thereof, and pivotal devices associated with said guiding devices to permit movement of the kerf cutter transversely of said laterally rigid element. 50
7. In a mining apparatus, the combination of an abutment adapted to be anchored in fixed position, a horizontally projecting kerf cutting mechanism having its weight supported independently of the abutment, guiding devices comprising laterally rigid elements pivotally connected with the abutment and engaging the kerf cutting mechanism to guide it rotatively about the abutment, and pivotal devices associated with said guiding devices to permit movement of the kerf cutting mechanism transversely of said laterally rigid elements. 60
8. In a mining apparatus, the combination with an abutment adapted to be anchored in fixed position, of a horizontally projecting kerf cutting mechanism, guiding devices comprising laterally rigid elements pivotally connected with the abutment and engaging the kerf cutting mechanism to guide it rotatively about the abutment, and pivotal devices associated with said guiding devices to permit movement of the kerf cutting mechanism transversely of said laterally rigid elements. 70

In testimony whereof, I affix my signature, in presence of two witnesses.
